UNITED STATES PATENT OFFICE.

GUSTAVE F. KRIESEL, OF MINNEAPOLIS, MINNESOTA, ASSIGNOR, BY MESNE ASSIGNMENTS, TO ESTHER V. SAFSTROM, OF MINNEAPOLIS, MINNESOTA.

ATTACHMENT FOR BORING AND MILLING MACHINES.

1,424,489.

Specification of Letters Patent. Patented Aug. 1, 1922.

Application filed April 28, 1919. Serial No. 293,172.

To all whom it may concern:

Be it known that I, GUSTAVE F. KRIESEL, a citizen of the United States, resident of Minneapolis, county of Hennepin, State of Minnesota, have invented certain new and useful Improvements in Attachments for Boring and Milling Machines, of which the following is a specification.

My present invention relates to an adjunct or auxiliary attachment used with the type of machine shown and described in my pending applications for Letters Patent of the United States, No. 167,819, filed May 10, 1917, and No. 230,412 filed April 24, 1918.

The object of this present invention is to provide means in connection with the hollow feed shaft of my boring machine for easily and quickly centering the work on the face plate and for re-adjusting the tools to vary the cut in boring a cylinder or other article without the necessity of removing the tool from the machine or displacing the work.

The invention consists generally in various constructions and combinations, all as hereinafter described and particularly pointed out in the claims.

In the accompanying drawings forming part of this specification,

Figure 1 is a vertical sectional view through a boring and milling machine embodying my invention.

Figure 2 is a front view of the upper portion of the machine, showing the supporting face plate and the clamps, thereon,

Figure 3 is a longitudinal sectional view through the hollow shaft, the supporting sleeve and a portion of the face plate, showing the position of the work thereon preliminary to the centering operation.

Figure 4 is a sectional view through the centering head,

Figure 5 is a sectional view on the line 5—5 of Figure 4,

Figure 6 is a sectional view on the line 6—6 of Figure 5,

Figure 7 is a sectional view showing the centering head in position in the cylinder.

Figure 8 is a similar view, showing the manner of mounting the tool in the head in place of the centering blocks.

Figure 9 is a detail view of the means for adjusting the tools and the scale by means

of which the degree of adjustment can be determined.

In the drawing, 2 represents the frame of the machine, having an upright face plate 3 secured to one end thereof and provided with an orifice 4 therein. 5 is a work-supporting table mounted on the front of the plate and 6 represents a series of clamps, radially mounted on the plate and by means of which a gas engine cylinder or other work is clamped securely over the orifice in the plate. 7 represents a sleeve, horizontally supported in bearings in the frame of the machine and having a rack 8 thereon that is engaged by a feed pinion 9 for the purpose of moving the sleeve forward or backward with respect to the orifice and the work. 10 represents a hollow shaft mounted in bearings in the sleeve 7 and provided with a gear 11 meshing with a pinion 12 on a shaft 13 that is driven through gears 14 and 15 from the shaft 16. By means of this mechanism the shaft 10 is fed forward or backward by the movement of the sleeve and at the same time is revolved in the sleeve to operate the tools.

The sleeve 7 is seated against a shoulder 10^a provided at the forward end of the shaft 10, and nuts 10^b engage an exteriorly threaded portion of the shaft 10 and the rear end of the sleeve for clamping it against the shoulder 10^a for a simultaneous forward or feeding movement of the sleeve and shaft, while allowing the shaft to revolve in the sleeve independently of the feeding movement. Bearings 17 are provided in the top of the frame for a shaft indicated in dotted lines whereon a milling tool (not shown) may be mounted.

The details of the feed mechanism I do not illustrate in this application, as it forms no part of my present invention.

The hollow shaft 10 has its exteriorly threaded end 18 projecting beyond the sleeve 7 for supporting a centering head or tool carrier 19, according to the work to be performed. A rod 20 is fitted concentrically within the hollow shaft 10 and at its outer rear end is provided with a finger grip 21 having a hub 22 that is seated against the end of a collar 23 secured on the shaft 10. The peripheral surfaces of the collar and hub are preferably marked off in a series of graduations 24 to form a micrometer scale by

means of which the person revolving the rod can accurately determine the degree of movement. The rod has a longitudinal socket 25 therein and a loose pin 26 fitting in the wall 5 of the socket and a tapered spindle 27 is threaded at 28 in the end of the rod and is provided with a finger grip 29. When this spindle is screwed into the socket, its tapered end will engage the pin 26 and force it outwardly against the wall of the shaft and thereby lock the shaft and rod against relative movement. When the tapered spindle is retracted, and the pin released, the rod may be revolved in the shaft to obtain the 10 desired adjustment of a centering head or the tools.

The opposite end of the rod has a squared portion 30 to enter a correspondingly shaped socket provided in a bevel gear 31 mounted 20 in the head 19. The head 19 is provided with a plurality of radial guides 33 in which centering blocks 34 are mounted to slide and are provided with internally threaded sockets 35 to receive the threaded ends of studs 25 36 on beveled pinions 37 arranged around the bevel gear 31 and meshing therewith. The studs 36 are held against longitudinal 20 movement by the engagement of the gears 37 with shoulders 38 on one side of the gears 30 and abutments on a head 39 held centrally in the head 19 by screws 32 so that the gears 37 and the studs 36 when revolved by the gear 31 will have no longitudinal movement but will feed the centering blocks 34 back 35 and forth in the guides in a direction depending on the direction of movement of the operating rod and the gear 31. When the centering blocks are projected, they will engage the inner surface of the cylinder or 40 other articles to be centered and the clamps of the cylinder on the face plate being loosened sufficiently, the cylinder will be moved by the pressure of the centering blocks until it is exactly concentric with the tool carrying 45 shaft. When this has been done, the clamps are tightened and the cylinder securely locked in position to be bored or for whatever work is to be done upon it.

The gear 31 preferably has hub bearings 50 in a ring 40 seated in the head 19, held in place by screws 41, and the gear is counter-bored to receive a rounded portion of the head 39 as an additional bearing. The centering blocks 34 may be provided with sockets 55 42 adapted to receive a tool 43 secured in the socket by a suitable means, such as a set screw 44. When this screw is tightened, the tool will be securely locked in the block and held firmly while at work. The same 60 blocks may, therefore, be used for centering purposes and as supports for the tools, the latter being removed when the blocks are used for centering the work with respect to the tool supporting shaft. Of course, if preferred, these centering blocks may be re-

moved entirely from the head and specially constructed tool carrying blocks substituted therefor.

In case it is desired to readjust the tools in the head, the supporting shaft and the sleeve may be withdrawn until the head is in the position shown in Figure 3, when the spindle 27 may be loosened and then by turning the finger grip 22 and watching the scale of the hub of this grip and the adjacent collar, the tools may be projected a greater distance to increase the cut in the wall of the cylinder or retracted, if preferred, to adapt the tools for a cylinder with a different bore, all without the necessity of removing the tools from the head or changing the position of the cylinder or other work on the face plate. I am thus able to save the labor of removing or readjusting the work in the machine and all readjusting of the tools to change the degree of cut thereof. Furthermore, the simultaneous adjustment of the tools by the mechanism described will insure an exact movement thereof and the certainty of each tool projecting precisely the same 90 distance from its supporting head.

I claim as my invention:

1. The combination, with a frame, of a hollow shaft mounted therein, means for revolving and feeding said shaft, a head 95 mounted on said shaft, blocks mounted for radial movement in said head, a device mounted in said head for both projecting and withdrawing said blocks, and a rod within said hollow shaft having an operating 100 means at one end and engaging said projecting and retracting means at the other end.

2. The combination, with a frame, of a hollow shaft mounted for rotary and longitudinal movement therein, a head mounted 105 on said shaft, means for clamping a cylinder or other work on said frame in position to receive said head, means for mounting centering blocks or tools in said head, and means operating through said hollow shaft 110 for both projecting and retracting said centering blocks and said tools.

3. The combination, with a frame, of a hollow shaft, a sleeve having bearings 115 therein for said shaft and mounted for forward and backward movement in said frame, means for clamping a cylinder or other work on said frame opposite one end of said shaft, a head mounted on said shaft and provided with means for supporting tools, means for centering the cylinder or other work with respect to said head, and means fitting within said hollow shaft and operable at the end thereof remote from the work for operating 120 said centering means.

4. The combination, with a frame, of a hollow shaft mounted therein for rotary and longitudinal movement, a head carried by said shaft, means for securing a cylinder or other work in position to receive said head, 125

blocks mounted for radial movement in said head, a rod fitting within said hollow shaft and operatively connected with said blocks to both project and withdraw them when it is revolved, a finger grip secured on the end of said rod remote from said head for revolving it in said shaft, means for measuring the degree of movement of said rod, and means for locking said rod in its adjusted 10 position on said shaft.

5. The combination, with a frame, of a sleeve having a rack bar and a pinion engaging said bar to reciprocate said sleeve, a hollow shaft having bearings in said sleeve to 15 revolve therein and having a forward and backward movement with said sleeve, mechanism for revolving said shaft in said sleeve, a tool holder carried by said shaft, a rod fitting within said hollow shaft and having 20 means at one end for adjusting the tools in said holder forward and backward, and means at the other end of said shaft remote from said holder for operating said rod to perform both the forward and backward adjustment of said tools, and a support for a 25 piece of work opposite said tool holder.

6. The combination, with a frame having an opening therein and a surface around said opening forming a seat for articles and 30 means for clamping the articles on said seat, a hollow shaft mounted for longitudinal and rotary movement in said frame, a holder mounted on one end of said shaft, centering blocks radially movable in said holder and 35 adapted to engage the walls of the article, such as an engine cylinder, when the holder is inserted therein, a rod fitting within said shaft and having means for engaging said centering blocks for forcing them against 40 the walls of the cylinder and centering it in said clamps with respect to said holder and shaft, and means at the end of said shaft remote from said holder for operating said rod to adjust said blocks.

45. 7. The combination, with a frame having an upright plate thereon provided with an opening and clamps around said opening for holding a piece of work, such as an engine cylinder, of a hollow shaft mounted for longitudinal and rotary movement in said frame, a holder carried by said shaft and having blocks radially movable therein, a gear mounted in said holder and operatively connected with said blocks for 50 projecting or retracting them, a rod fitting within said hollow shaft and engaging said gear to revolve it and operate said blocks, and mechanism at the end of said shaft remote from said holder for operating said rod to move said blocks into engagement 55 with the wall of the cylinder for centering it in its clamps on said plate.

60. 8. The combination, with a frame having an opening therein and means for clamping a piece of work, such as an engine cylinder,

on the surface of said frame around said opening, a hollow shaft mounted in said frame for a reciprocating and rotary movement, a holder mounted on said shaft and having radial guides therein, tool supporting 70 blocks mounted in said guides, said holder being adapted to enter the cylinder when said shaft is projected, a rod mounted in said shaft and having means at one end for projecting and retracting said blocks and 75 tools, and means at the other end of said shaft remote from said holder for operating said rod and said blocks.

9. The combination, with a frame, of a hollow shaft mounted therein, means for revolving and feeding said shaft, a head mounted on said shaft and provided with radial tool guides, a rod fitting within said hollow shaft and having means at one end for projecting and retracting the tools in 80 said guides, and means at the other end of said shaft remote from said head for operating said rod to perform the adjustment of the tools.

10. The combination, with a frame, of a hollow shaft mounted therein, means for revolving and feeding said shaft, a head mounted on said shaft and provided with radial guides for centering blocks and tools, means fitting within said shaft and having 85 one end adapted for positively projecting said centering blocks to center the work with respect to said shaft and for projecting and retracting the tools in said guides, and means at the other end of said shaft remote 100 from said head for operating said projecting and retracting means.

11. The combination, with a frame having an orifice therein and a true seating surface around said orifice, and clamps for securing 105 a piece of work, such as an engine cylinder, in front of said orifice, a hollow shaft supported in said frame for a revolving and for forward and backward movement, a head mounted on said shaft and adapted to pass 110 through said orifice and enter the bore of the cylinder secured to said frame, said head having radial guides therein and centering blocks and tools, a rod fitting within said shaft and having one end adapted to positively project and retract said blocks, and 115 tools in said guides for centering the work and for moving the tools toward and from the work, and means at the other end of said rod remote from said head for operating said rod to project and retract said blocks and tools.

12. The combination, with a frame and means for supporting a piece of work thereon, of a tool supporting head and a support 125 therefor mounted to be moved toward and from the work, said head having radial guides therein to receive centering blocks or tools, and a single means concentric with said head and mounted to project and re- 130

tract the centering blocks or tools mounted in said guides.

13. The combination, with a frame and means for supporting a piece of work thereon, of a shaft mounted to revolve and for forward and backward movement in said frame, a tool carrying head mounted on said shaft and a single means concentric with said shaft for moving the tools radially in 10 said head to advance or retract them with respect to the work.

14. The combination, with a frame and means for clamping a piece of work thereon, of a shaft having a tool carrying head, 15 means for revolving said shaft to feed the tools to the work, said shaft being mounted for forward and backward movement with respect to the work and a device mounted lengthwise of said shaft for moving the 20 tools radially in said head to both project, and retract them with respect to the work.

15. The combination, with a frame and a plate mounted thereon having an orifice therein and a true seating surface around 25 said orifice and means for clamping a piece of work on said true surface, of a shaft mounted in said frame for movement forward and backward with respect to said ori-

fice, a tool carrier mounted on said shaft and adapted to be projected through said orifice 30 to engage the work, the tools being mounted for radial movement in said carrier and means mounted in said shaft lengthwise thereof for operating said tools to project or withdraw them with respect to the work. 35

16. The combination, with a frame and a plate mounted thereon having an orifice therein and a true seating surface around said orifice and means for clamping a piece of work on said true surface, of a shaft 40 mounted in said frame for movement forward and backward with respect to said orifice, a tool carrier mounted on said shaft and adapted to be projected through said orifice to engage the work, the tools being 45 mounted for radial movement in said carrier, means mounted in said shaft lengthwise thereof for operating said tools to project or withdraw them with respect to the work, and means at the end of said shaft remote from the tool carrier for adjusting said tool-operating means. 50

In witness whereof, I have hereunto set my hand this 19th day of March, 1919.

GUSTAVE F. KRIESEL.
